UNITED STATES PATENT OFFICE.

SAMUEL KANNER, OF NEW YORK, N. Y.

DESIGN FOR A PEN DESK STAND OR SIMILAR ARTICLE.

Application filed February 5, 1927. Serial No. 20,632. Term of patent 7 years.

To all whom it may concern:

Be it known that I, SAMUEL KANNER, a citizen of the United States, residing at New York, in the county of New York and the State of New York, have invented a new, original, and ornamental Design for a Pen Desk Stand or Similar Article, of which the following is a specification, reference being had to the accompanying drawing, forming a part thereof, and in which—

I claim:

The ornamental design for a pen desk stand or similar article, as shown.

SAMUEL KANNER.
